CLAIM

The ornamental design for a housing for a dual reel tape cartridge, as shown and described.

DESCRIPTION

FIG. 1 is a three-quarter perspective view of an embodiment of a housing for a dual reel tape cartridge showing my new design;

FIG. 2 is a plan view thereof;

FIG. 3 is a plan view thereof;

FIG. 4 is an elevational view of the left side thereof;

FIG. 5 is an elevational view of the right side thereof;

FIG. 6 is an elevational view of the back thereof; and,

FIG. 7 is an elevational view of the front thereof.

In the drawings, the broken lines are for illustrative purposes only and form no part of the claimed design.
